US0D1007476S

(12) **United States Design Patent** (10) Patent No.: **US D1,007,476 S**
 Tordjman (45) Date of Patent: ** Dec. 12, 2023

- (54) **REMOTE CONTROL (WIRELESS)**
 (71) Applicant: **SOMFY ACTIVITES SA**, Cluses (FR)
 (72) Inventor: **Jonathan Tordjman**, Sevres (FR)
 (73) Assignee: **SOMFY ACTIVITES SA**, Cluses (FR)

(**) Term: **15 Years**

(21) Appl. No.: **35/514,619**

(22) Filed: **Jun. 3, 2022**

(80) **Hague Agreement Data**

Int. Filing Date: **Jun. 3, 2022**

Int. Reg. No.: **DM/221630**

Int. Reg. Date: **Jun. 3, 2022**

Int. Reg. Pub. Date: **Jul. 1, 2022**

(30) **Foreign Application Priority Data**

Dec. 10, 2021 (EM) 008793608-0002

(51) **LOC (14) Cl.** **14-03**

(52) **U.S. Cl.**

USPC **D14/218**

(58) **Field of Classification Search**

(57) **CLAIM**

The ornamental design for a remote control (wireless), as shown and described.

DESCRIPTION

1. Remote control (wireless)

1.1 : Perspective

1.2 : Front

1.3 : Back

1.4 : Right

1.5 : Left

1.6 : Top

1.7 : Bottom

The dashed broken lines illustrate portions of the article, and form no part of the claimed design.

1 Claim, 7 Drawing Sheets
